(57) **CLAIM**

The ornamental design for wireless earbuds and wearable charger and integrated speaker, as shown and described.

DESCRIPTION

FIG. 1 is a front perspective view of the ornamental design for a first embodiment of a wearable charger and integrated speaker according to my invention;

FIG. 2 is a rear perspective view thereof;

FIG. 3 is a front view thereof;

FIG. 4 is a rear view thereof;

FIG. 5 is a side view thereof;

FIG. 6 is an opposing side view thereof;

FIG. 7 is a top view thereof;

FIG. 8 is bottom view thereof;

FIG. 9 is a front view of the ornamental design for a second embodiment of a wearable charger and integrated speaker according to my invention;

FIG. 10 is a rear perspective view thereof;

FIG. 11 is a front view thereof;

FIG. 12 is a rear view thereof;

FIG. 13 is a side view thereof;

FIG. 14 is an opposing side view thereof;

FIG. 15 is a top view thereof; and,

FIG. 16 is bottom view thereof.

The broken lines are illustrative of environmental structure only and form no part of the claimed design.

1 Claim, 16 Drawing Sheets
